UNITED STATES PATENT OFFICE.

WILLIAM LEWISTON PLAYMAN, OF STEVENS POINT, WISCONSIN.

DESIGN FOR A COMBINED BABY CABINET AND BASKET-CRIB SUPPORT.

60,160.

Specification for Design.

Patented Jan. 3, 1922.

Application filed April 1, 1920. Serial No. 370,573. Term of patent 3½ years.

To all whom it may concern:

Be it known that I, WILLIAM L. PLAYMAN, a citizen of the United States, residing at Stevens Point, in the county of Portage and State of Wisconsin, have invented a new, original, and ornamental Design for a Combined Baby Cabinet and Basket-Crib Support, of which the following is a specification, reference being had to the accompanying drawing, forming part thereof.

The figure is a perspective view of a baby cabinet and basket crib support, showing my new design.

I claim:

The ornamental design for a combined baby cabinet and basket crib support, as shown.

WILLIAM LEWISTON PLAYMAN.
